CLAIM

The ornamental design for a security camera, as shown and described.

DESCRIPTION

FIG. 1 is a top, front, and right-side, top perspective view of a security camera;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The dashed broken lines depict portions of the security camera that form no part of the claimed design. The dot-dashed broken lines denote the boundary of the claim and form no part of the claimed design.

1 Claim, 7 Drawing Sheets
